UNITED STATES PATENT OFFICE.

WILLIAM T. WOOD, OF WASHINGTON, DISTRICT OF COLUMBIA.

FILE CASE OR CABINET.

SPECIFICATION forming part of Letters Patent No. 403,168, dated May 14, 1889.

Application filed December 14, 1888. Serial No. 293,547. (No model.)

To all whom it may concern:

Be it known that I, WILLIAM T. WOOD, of Washington, in the District of Columbia, have invented certain Improvements in File Cases or Cabinets, of which the following is a specification.

My invention relates to those so-called "filing-cases" in which the file-boxes are mounted in horizontal and vertical rows in a case or cabinet and provided with means by which they are automatically suspended when withdrawn.

The invention relates to an improved mode of constructing the case or cabinet, whereby its parts are adapted to be cheaply constructed by machinery and to be quickly assembled or disconnected without the employment of skilled labor.

The invention also consists in an improved construction of the devices by which the boxes are suspended.

In the accompanying drawings, Figure 1 is a side elevation of a case constructed on my plan. Fig. 2 is a front elevation of the same. Fig. 3 is a vertical section from front to rear on the line *xx*, Figs. 2 and 4. Fig. 4 is a top plan view of the case with portions shown in horizontal section. Fig. 5 is a vertical cross-section on the line *yy* of Figs. 3 and 4. Fig. 6 is a perspective view showing the parts or members of the case and the manner in which they are assembled. Fig. 7 is a perspective view showing the bottom of the file-box and the suspending devices thereon.

In its preferred form my case is constructed entirely of metal. It consists of front standards, A, rear standards, A', horizontal bars or rails B, connecting the front and rear standards, and transverse rods or tubes C, passing through the standards and the ends of the bars B. The standards are constructed each in one piece and of U form in horizontal section, with transverse openings a therethrough. The bars B are also constructed of metal of U form, in cross-section, with horizontal lips or flanges b turned outward along the lower edges. These flanges terminate before reaching the ends of the bars, which are flanged and adapted to fit snugly within the hollow standards A and A', as shown. The ends of the bars B thus formed are provided with transverse holes b', adapted to register with

the holes a in the standards. Each of the ends is also provided with a vertical slot or opening, b², intersecting the opening b' and adapted to receive a vertical wedge or key, b³. The bars C are made of a round form, either solid or tubular, as preferred, and of suitable diameter to fit snugly within the holes a and b'.

In assembling the parts the ends of the bars B are inserted within the respective standards and the bars C passed therethrough. The standards are then adjusted at proper distances apart to admit of the file-boxes sliding between them, after which the keys b³ are inserted and driven tightly home, their effect being to bind the several parts firmly together. The resulting structure presents, as shown in the drawings, a series of compartments or openings, each adapted to receive and sustain a file-box, D. The boxes are inserted and withdrawn horizontally at the front, each box passing inward over the bars C between the standards and between the horizontal rails or bars B on top of the flanges b, by which they are sustained.

I prefer to construct the standards and the horizontal rails of sheet-steel; but they may be rolled, cast, or otherwise formed of other metals.

The case may be provided with suitable base and top and closed at the sides and back in any appropriate manner, these features constituting no part of my invention.

As regards the standards, the essential requirement is that they shall be of hollow or channeled form, and as regards the bars B the essential requirement is that they shall present the side flange to sustain the file-boxes. Provided these features are retained the said parts may be modified in sectional form at will. The rear standards are usually made of greater width than the front standards in order to serve as stops to arrest the backward movement of the boxes.

While I propose in ordinary cases to construct the entire case of metal, it is manifest that its parts may be constructed of wood, provided they are constructed and united in precisely the same manner as the metal boxes above described.

In order to provide for automatically suspending the file-box, I provide each box on the under side with two plates, d, located

near the sides and about midway of the length of the box. Each plate has its end curved downward and forward from the bottom of the box and then extended outward in the form of a lip, as plainly shown in Fig. 7. It will be observed that the flanges *b* of the sustaining-rails terminate at a short distance from the front bars, *C*, leaving intermediate vertical spaces, such as shown at *b*⁴, Figs. 3 10 and 4.

The file-box is introduced by first turning its base to an upright position and then hooking the plates *d* downward over the front bar, *C*, as shown in the lower part of Fig. 3, the 15 lower ends of the plates *d* passing downward through the spaces and openings *b*⁴. In this manner the box is suspended in front of the cabinet. Its forward end is then turned upward until the base of the box assumes a 20 horizontal position, after which the box is pushed horizontally into the case, its base riding on top of the flanges *b*, while the ends of the plates *d* pass beneath said flanges, as clearly shown in Figs. 3 and 5, thus preventing 25 the boxes from tipping upward or outward until they have been withdrawn a sufficient distance for the plates or hooks *d* to engage the bar *C*.

I am aware that file-boxes have been variously provided with suspending hooks or plates to engage horizontal guide-rails; but I believe myself to be the first to construct and arrange these suspending-plates in such manner that they will underride the horizontal 35 guide and escape vertically at its forward end between the guide and a supporting-rod and its equivalent.

The back and sides of my case may be closed in any suitable manner. I recommend, 40 however, as a simple and desirable construction the employment, as shown in Fig. 4, of the metal backing-plates *c'*, introduced vertically between the rear rods, *C*, and the verti-

cal flanges of the rear standards, *A'*. The plates thus applied will be held securely in 45 position without special fastening devices. They may be quickly inserted and removed, and they add materially to the rigidity of the structure.

Having thus described my invention, what I 50 claim is—

1. The knockdown cabinet for file-boxes, consisting of standards *A* *A'*, the independent flanged bars *B*, and cross-bars *C*, passing through and uniting the standards and bars 55 *B*, substantially as shown.

2. In a case for file-boxes, the channeled standards, the bars *B*, fitted at their ends therein, the transverse rods uniting the standards and bars, and the keys, applied substantially as shown. 60

3. A file-case having a front suspension-rod, *C*, and box-sustaining bars with side flanges separated from the rod by an opening, *b*⁴, in combination with a file-box having 65 suspending plates or hooks adapted to pass through the openings and underride the bars, whereby the box is guided within the case and automatically arrested and suspended when withdrawn in position to be disconnected. 70

4. A case for file-boxes, having the front standards, the rear standards of greater width, and the intermediate flanged rails, whereby 75 the boxes are sustained.

5. In a file case or cabinet, the combination of the standards *A'*, the cross-rods *C*, and the plates *c'*, inserted between the rods and standards, substantially as described and shown.

In testimony whereof I hereunto set my 80 hand, this 4th day of December, 1888, in the presence of two attesting witnesses.

WILLIAM T. WOOD.
